STRAP TENSIONER

Joseph D. Lewis, Jr., Chattanooga, Tenn., assignor to
Universal Packaging, Inc., East Ridge, Tenn.

Filed Jan. 27, 1972, Ser. No. 215,994

Term of patent 14 years

Int. Cl. D8—08

U.S. Cl. D8—44

FIG. 2

FIG. 1

FIG. 3

FIG. 4

FIG. 5

FIG. 1 is a top plan view of the strap tensioner embodying my new design;

FIG. 2 is a side elevational view of one side of the strap tensioner of FIG. 1 with a portion broken away for clarity of illustration;

FIG. 3 is a side elevational view of the tensioner of FIG. 1 opposite to the side elevational view of FIG. 2;

FIG. 4 is a bottom plan view of the strap tensioner of FIG. 1; and

FIG. 5 is an end elevational view of the strap tensioner taken from the right side of FIG. 4.

I claim:

The ornamental design for a strap tensioner, as shown.
